ATTORNEY

UNITED STATES PATENT OFFICE

BERTRAM E. MESLER, OF BROOKLYN, NEW YORK

SHADE ROLLER STOP

Application filed March 28, 1930. Serial No. 439,757.

This invention relates, primarily, to improvements in shade roller stops; and the principal object, in that connection, is to provide a novel keying device, for quick and easy attachment to and anchorage on a wooden shade roller to which the shade roller stop is applied, and also for simplifying the construction and cheapening the cost of a shade roller stop of the general type disclosed in U. S. Patent to me No. 1,765,170.

In the accompanying drawings, wherein there are illustratively shown an embodiment of said keying device as at present preferred, and a shade roller stop pursuant to said co-pending application but of a modified construction for co-acting pursuant to present preference with the keying device just mentioned:

Fig. 1 is a perspective view of a shade roller provided with a stop adapted to include a keying device according to the invention, and mounted upon a window casing.

Fig. 2 is an enlarged vertical longitudinal sectional view through one end of the shade roller showing, as part of such stop, a preferred embodiment of said keying device,—with the stop parts shown in lowered shade position.

Fig. 3 is a view similar to Fig. 2 but showing the position of the parts when the shade is raised to the intended limit.

Fig. 4 is a vertical transverse sectional view on the line 4—4 of Fig. 2.

Fig. 5 is a collective perspective view of the several stop parts.

It is preliminarily pointed out that, in Figs. 1 and 2, as in my said patent, the numeral 10 designates a shade roller having a flexible shade 11 windable thereon, the free edge 12 of which shade carries the usual reinforcing strip from which a pull cord 13 depends. The roller, as is well known, is hollow for the purpose of housing a helical spring 14, which, when wound up, places the roller under tension for winding the shade from a lowered position to a raised position; a suitable ratchet mechanism (not shown) being provided for locking the shade in a lowered position against winding, and having associated therewith a flat trunnion 15 ex-

tending from one end of the roller 10 to fit into a holding slot in a supporting bracket 16 fixedly secured to one of the sides of the window casing 17.

Referring now to the keying device of the present invention, the same is illustrated in Figs. 2 to 5, as embodying a unitary metal fitment fixed to the shade roller 10 adjacent the end supported in the bracket 16.

This keying device 18, is here shaped to include a cylindrical head 19, a shank 20, and a blade-like lower terminus 21; the device 18 having been found to be applicable, by mere finger pressure on the top of head 19, to cause the curved and sharp lower rounded edge of terminus 21 to pierce the comparatively soft wood commonly found as the material of which the roller 10 is made. The grain of such wood running longitudinally of the roller, the device 18, during this piercing operation, is arranged at a 90° removal from the position shown in Figs. 2 to 5, that is, with the terminus 21 parallel to said grain; and when the shank 20 is completely down in the wood, the device 18 is rotated 90° to arrange the terminus 21 at right angles to said grain. This final condition, as illustrated in Figs. 2 and 4, shows the upper blunt edges of the terminus 21 locked against the inner surface of the hollow in the roller containing spring 14; an ideal condition. In any event, however, when the device 18 is applied to a wooden roller as above, the terminus 21 will extend at an angle to the grain of such wood, thus to lock the device against withdrawal; whether or not the shank 20 only, or both said shank and the terminus, be finally embedded in the wood.

Head 19 of this keying device 18 is slotted on opposite sides as clearly shown in Figs. 2 to 5, such slots being marked 19a; thereby providing above and below each such slot a rib 18b.

Referring now finally to the other parts of the stop illustrated, which are identical with or substantial equivalents of parts claimed as stop elements in said copending application, these parts may be briefly described, as follows:

The slots 19a of the keying device of the

present invention inter-engage with the side walls of a slot 22 cut longitudinally of the cylindrical wall 23 of a sleeve member 24. If a plurality of keying devices are embedded in the roller, such sleeve member may be provided with one more additional slots like the slot 22, for instance, as indicated at 22' in Fig. 5; but such duplications are deemed unnecessary. This is so, because when a device 18 is arranged with its terminus 21 at an angle to the wood grain as shown, it cannot be withdrawn from the roller; and with member 24 in place on the roller, the device 18 cannot be rotated about its shank axis to disturb said angle.

The interior wall of the sleeve member is screw threaded as at 25 for threaded engagement with the exterior threads 26 provided on a cap member 27. The end wall of the cap member 27 is provided with a cruciform slot 28 affording the equivalent of two intersecting elongated slots through either of which the flat trunnion 15 may be extended in assembling the parts to have the cap member fit 25 over the end of the roller and to arrange the elements as shown in Figs. 2, 3 and 4. Both the keying device 18 and the sleeve member 24, but not the cap member 27, rotate with the roller 10, with the result that, due to threads 25 and 26, longitudinal sliding movement is imparted to the sleeve member 24 while there is a relative rotation or spiralling movement between members 24 and 27. Assuming that the shade is in lowered position, the parts are 30 as shown in Fig. 2 of the drawings; that is, the outer end 24a of the sleeve member 24 is in spaced relation to the shade bracket 16 and the device 18 is adjacent to the inner end of the slot 22. Upon the actuation of the pull 35 cord 13 to release the ratchet mechanism, the spring 14 imparts a winding movement to the roller 10, and during this winding movement, the sleeve member 24 is fed outwardly until the outer end 24a thereof contacts with the 40 bracket 16, thus arresting movement and bringing the roller, gently, to a stop.

While I have described what I deem to be the most desirable embodiment of my invention, it is obvious that other embodiments are 45 possible, and other uses of such embodiments, without in any way departing from the spirit of my invention, and I therefore do not limit myself to the exact details of construction herein set forth nor to anything less than the whole of my invention limited only by the appended claim.

I claim:

In combination with a shade roller and an axially movable sleeve constituting a limiting 50 stop for the roller after a prescribed number of revolutions, the sleeve having a slot opening at one end, a key member to preclude relative angular movement of the roller and sleeve comprising a head formed with parallel 55 flats in diametrically opposite sides, a shank

having a length the thickness of the enclosing wall of the shade roller spring and extending from said head, and a T-head at the opposite end of the shank, the T-head being tapered to a point for penetration through the shade 70 roller wall and its longer dimension lying in a vertical plane at an angle to the vertical planes of said flats.

In testimony whereof I hereby affix my signature.

BERTRAM E. MESLER.
